FAUCET HANDLE

Stephen A. Young, Monticello, Ind.
(Flora, Ind.)

Filed Oct. 16, 1961, Ser. No. 67,075

Term of patent 14 years

(Cl. D91—3)

Fig. 1

Fig. 2

Fig. 3

FIGURE 1 is a top plan view of a faucet handle embodying my new design.

FIGURE 2 is a bottom plan view of the same.

FIGURE 3 is a side elevation of the same.

I claim:

The ornamental design for a faucet handle, substantially as shown.
